(57) **CLAIM**

The ornamental design for a liquid crystal projector, as shown and described.

DESCRIPTION

FIG. 1 is a front, top and right side perspective view of a liquid crystal projector, showing our new design;

FIG. 2 is a reduced exploded perspective view with both sides in an open position;

FIG. 3 is a front elevational view of FIG. 1;

FIG. 4 is a rear elevational view thereof;

FIG. 5 is a top plan view thereof;

FIG. 6 is a bottom plan view thereof; and,

FIG. 7 is a right side elevational view thereof; the opposite side being a mirror image thereof.
